BUTTON COMPANY, OF WATERBURY, CONNECTICUT, A CORPORATION OF CON-
NECTICUT.

CONNECTING-ROD.

1,172,574.

Specification of Letters Patent. Patented Feb. 22, 1916.

Application filed June 26, 1915. Serial No. 36,419.

To all whom it may concern:

Be it known that I, FRANKLIN R. WHITE, a citizen of the United States, and a resident of Waterbury, in the county of New Haven 5 and State of Connecticut, have made and invented certain new and useful Improvements in Connecting-Rods, of which the following is a specification.

My invention relates to connecting rods 10 or pitmen of the kind or type commonly designated as longitudinally yieldable pitmen, and which include a spring or equivalent yieldable element through which force is transmitted when the rod is in use, to the 15 end that the rod may yield in case excessive resistance is encountered by the device or element to which motion is communicated or in case for any reason the force transmitted through or along the rod becomes excessive.

My improved connecting rod is designed with especial reference to use in button attaching machines to adapt the same for use with fabrics of different thicknesses, or fabrics made up of two or more thicknesses of material. In such machines the button while being attached is pressed firmly against the material by means of a suitable plunger, while at the same time crushing of 30 or injury to the button has to be avoided. Both these ends are secured in the use of my improved connecting rod, for the length thereof is made such that when the machine is operating upon a fabric of the normal or 35 average thickness the button will be pressed against the fabric with a given predetermined force, while if a thicker fabric is used, or one comprising two or more thicknesses of material, the rod will yield before the plunger is pressed against the button with 40 sufficient force to crush or injure it. It will be understood, however, that a connecting rod made in accordance with my invention is capable of general use, and is not limited 45 to the use above suggested; and that while the drawing accompanying and forming a part of this application illustrates the preferred embodiment of my invention the same may be variously modified and embodied in other specific forms by those skilled in the art to which my invention relates.

In the drawing: Figure 1 is a view showing my improved connecting rod in side ele-

vation; and Fig. 2 is a view showing a section of the same taken upon a central longitudinally extending plane indicated by the line 2—2, Fig. 1, the parts being shown on a larger scale than in Fig. 1.

In the drawing, the reference numeral 3 designates a suitable cage having side bars 4 and arms 5 at its upper end through which one end of the connecting rod may be connected with an operating member or a member to be operated. The cage in question is 60 designed to contain a coil spring 6 through which force is transmitted when the rod is in use; and the same is provided with a guide 7 at its upper end and formed integrally with the body of the cage whereby its 65 position is fixed relative to the cage, and with a removable guide 8 located at its lower end and in threaded engagement with the cage. The upper end of the spring abuts 70 against the guide 7 as shown.

The reference numeral 9 designates a rod having an eye 10 at its lower end whereby the other end of the connecting rod may be connected with an element of a machine to or from which motion is to be communicated, and which rod extends through the removable guide 8 and is provided with an extension 11 of reduced cross-section which extends through the coil spring and cage aforesaid and into the fixed guide 7, whereby the rod is guided as it moves longitudinally of the cage when sufficient resistance is encountered to compress and shorten the spring 6. It will be understood, however, 80 that the spring acts normally as a transmitting member of fixed length, and that the force of the spring is overcome and the rod moved independent of the cage only in case excessive resistance is encountered by the element to which motion is communicated 85 through or by means of the rod or pitman 90 considered as a whole.

The rod 9 is provided with a threaded shoulder 12 at the lower end of the reduced extension 11 which shoulder carries an internally threaded collar 13 which abuts against the upper or inner end of the removable guide 8, and which collar is firmly supported upon the rod by engagement with the threads and by the ledge 14 at the lower 100 end of the thread. The upper end 15 of the shoulder 12 preferably terminates in the same plane as the upper end of the collar 105

13, so that the lower end of the spring rests upon both the upper end of the collar and the end of the shoulder.

It will be appreciated that the thrust 5 transmitted through the rod is taken up by the collar 13, and that a strong connection has to be provided between the rod 9 and the collar in order that the collar may not become loose on the rod, or possibly broken 10 when the device is in use. In my improved connecting rod the collar is supported by both the threads upon the shoulder 12 and the ledge 14 at the lower end thereof; and, in addition, in case the upper end of the 15 shoulder bears directly against the lower end of the spring, as in the form of my invention illustrated, the thrust transmitted through the connecting rod considered as a whole is distributed between the 20 collar and the shoulder 12, which shoulder, as will be understood, is formed integrally with the rod 9; whereby excessive strength is provided for the elements through which 25 force is transmitted from the rod 9 to the spring and cage.

Having thus described and explained my invention, I claim and desire to secure by Letters Patent:

1. In a device of the class described, an 30 elongated cage adapted to contain a spring, a fixed guide at one end of said cage, a removable guide located at the opposite end of said cage; a rod extending through said removable guide and having a shoulder, and 35 an extension of reduced diameter, which

extension extends through said cage and into said fixed guide; a collar located upon said shoulder and abutting against the inner end of said removable guide; and a coil spring located within said cage and surrounding the reduced extension of said rod, one end of said spring bearing against said fixed guide and the other against said collar and the inner end of said shoulder. 40

2. An apparatus of the class described 45 comprising a cage adapted to contain a spring, guides at opposite ends of said cage forming spaced confronting shoulders, a rod extending through and slidably engaging the side walls of one of said guides, said rod being provided with a shoulder and an extension projecting from said shoulder coaxially with said rod, said extension being of reduced diameter and slidably engaging in the other of said guides, a collar located 50 upon said shoulder and abutting against the inner end of one of said guides, and a coil spring located within said cage surrounding the reduced extension of said rod, one end of said spring bearing against said 55 collar and rod shoulder, and the opposite end bearing against one of said guides. 60

Signed at Waterbury, in the county of New Haven and State of Connecticut, this 8 day of June, A. D. 1915.

FRANKLIN R. WHITE.
